UNITED STATES PATENT OFFICE.

THOMAS C. KENNEDY, OF CHICAGO, ILLINOIS.

WATER COOLER.

Application filed November 1, 1919. Serial No. 335,160.

To all whom it may concern:

Be it known that I, THOMAS C. KENNEDY, a citizen of the United States, residing at Chicago, in the county of Cook and State of

5 Illinois, have invented certain new and useful Improvements in Water Coolers, of which the following is a specification.

This invention relates to water coolers.

More particularly it relates to a water 10 cooler adapted to be associated with a refrigerator.

The ordinary refrigerator water cooler comprises a reservoir or compartment attached to or set in a refrigerator within or 15 near the ice chest and having a faucet thru which the water may be drawn off. The coolers, particularly when they are permanently attached to the refrigerator, are difficult to clean or to repair when leaks 20 occur, and the faucet and outlet pipe cannot be cleaned or repaired without losing or polluting the chilled water.

Where the coolers are of the detached type, they cannot be removed without considerable 25 difficulty in loosening the pipe connections and if only the faucet and outlet pipes are to be cleaned or repaired, the chilled water is lost or must first be drawn off into a separate receptacle.

30 One of the objects of this invention is to provide an improved water cooler for a refrigerator.

Another object is to provide a cooler which may be readily removed and replaced.

35 Another object is to provide a cooler which may be removed without losing or drawing off the chilled water.

Another object is to provide a water cooler wherein the water reservoir, piping and faucets may be readily separated for cleaning and repairs.

Other objects and advantages will appear from the specification and claim.

An embodiment of the invention is illustrated in the accompanying drawing, wherein—

Fig. 1 is a front elevation showing a water cooler in position, and

50 Fig. 2 is a section of a portion of the cooler.

The cooler comprises a compartment or reservoir 5, mounted in the refrigerator. The reservoir may be made of any suitable material and in any desired shape to best 55 adapt it to the structure of the refrigerator with which it is to be used. It may be sus-

pended or otherwise secured to the top or sides of the ice or other compartment, or it may be set upon the floor of any compartment.

60

In the bottom of the reservoir is an outlet opening 6 thru which extends a nozzle 7. Nozzle 7 is provided with an annular flange 8 at its top. This annular flange rests on the bottom of the reservoir and is secured thereto in any desired manner, for example, soldering, to provide a water-tight joint. The upper edge of the opening thru the nozzle is chamfered to form a valve seat 9 for a valve in the form of a ball 10. The lower part of the nozzle is formed with a converging wall 11, extending some distance below flange 8.

When the reservoir is in place in the refrigerator, nozzle 7 extends into the open end 75 of an elbow pipe 15, which passes thru the wall of the refrigerator. The projecting end of pipe 15 is threaded to receive a faucet 16, for drawing off the water, and a nut 17. The wall of the refrigerator is 80 clamped between nut 17 and a flange 18 on the pipe.

The upper end of the elbow in pipe 15 is provided with an annular flange 20, which is grooved on its inner surface to receive a 85 gasket 21. The converging wall 11 of the nozzle wedges into gasket 21 to make a tight fit to prevent the escape of water.

The inner wall of the elbow of pipe 15 is provided with a threaded lug 22 into which 90 is screwed a threaded post or stem 23. Stem 23, when the reservoir is in place, supports ball 10 above seat 9, as shown by the full lines of Fig. 2, to allow the passage of water into pipe 15. The position of the ball above 95 its seat can be changed by varying the amount stem 23 is threaded into lug 22.

One or more guard posts 24 may be set into flange 8 to keep the ball in proper position above seat 9.

100

When the reservoir is to be removed for cleaning or repair or for the cleaning or repair of the pipe or faucet, the reservoir is lifted and taken out of the refrigerator. As the reservoir is raised the ball settles against 105 seat 9, effectively closing the opening in the reservoir to prevent the escape of the chilled water. The length of the converging wall 11 of the nozzle is made longer than the distance the ball is normally held above seat 9, 110 so that the ball is properly seated before the end of the nozzle emerges from the opening

in the elbow of pipe 15. There is consequently no leakage.

The reservoir may be removed and if only the pipe and faucet are to be cleaned or repaired, none of the chilled water is lost or polluted. The reservoir may be readily removed by simply raising it from position, no uncoupling of connections being necessary. It may be as readily replaced, whereupon 10 the valve automatically opens, allowing the free passage of water from the reservoir into and thru the pipe and faucet.

Having described my invention, what I claim is:—

15 In combination with a vertical wall of a refrigerator, a horizontal pipe, for extension thru said wall, threaded on its outer end to receive a faucet and having a collar for

contact with the inner surface of the wall and having an upturned flanged end for inclusion within a compartment of a refrigerator; a packing in the flange to receive a nozzle from a water reservoir; a water reservoir; a nozzle extending from the bottom thereof; a valve above the nozzle normally 25 closing said nozzle; a pin secured in the upturned end of said pipe arranged to extend through the nozzle to unseat the valve and a faucet threaded on the outer horizontal end of said pipe to permit the pipe to be taken 30 out of its normal operative position for cleaning when the faucet is removed.

In testimony whereof I hereunto subscribed my name.

THOMAS C. KENNEDY.
